Albert Brown

UNITED STATES PATENT OFFICE.

ALBERT BROWN, OF MENDOCINO, CALIFORNIA.

PAPER-BAG AND TWINE HOLDER COMBINED.

SPECIFICATION forming part of Letters Patent No. 288,204, dated November 13, 1883.

Application filed July 18, 1883. (No model.)

To all whom it may concern:

Be it known that I, ALBERT BROWN, of Mendocino, in the county of Mendocino and State of California, United States of America, have invented a new and Improved Paper-Bag and Twine Holder Combined; and I do hereby declare that the following is a full and exact description thereof.

This invention relates to an improved paper-bag holder and twine-holding device combined; and it has for its object to provide a device which shall be simple, convenient, and inexpensive.

My invention consists in the improved construction and arrangement of parts, which will be hereinafter fully described with reference to the drawings, in which—

Figure 1 is a perspective view of the device embodying my invention. Fig. 2 is a side view of the twine-holder detached, and Fig. 3 is a top view of the latter.

The same letters refer to the same parts in all the figures.

A in the drawings designates my improved bag-holder, which is in this case composed of the sides B B, bottom C, shelves D D, top E, and a central vertical partition, F. The construction of the bag-holder, however, may be modified, whenever desired, without departing from the spirit of my invention.

G designates the twine-holder, which consists, mainly, of a semi-spherical cap having slots H, and provided with a laterally-projecting arm, J. The said cap is hinged, as shown,

to a base-piece secured on top of the bag-holder, and provided at its front end with a staple, L, adapted to enter a slot, M, in the front end of the arm J. The cap may be locked in position by means of a hook, N, pivoted upon the top of the bag-holder.

The operation of this device is obvious. The ball of twine being placed in position in the spherical cap, its end may extend through any one of the slots in the latter, whereby it is rendered easy of access.

I claim and desire to secure by Letters Patent of the United States—

1. The combination, with the bag-holder, of a twine-holding device consisting, mainly, of a semi-spherical hinged shell having slotted sides, substantially as set forth.

2. The described twine-holder, consisting, mainly, of a base-plate, a hinged semi-spherical shell having slotted sides, and provided with a laterally-extending arm, and the locking device, substantially as set forth.

3. The combination, with a bag-holder, of a twine-holding device consisting, mainly, of a semi-spherical shell hinged to the top of the same, and having a laterally-extended slotted arm adapted to engage a fixed staple, and a locking-hook pivoted to the top of the said bag-holder, substantially as and for the purpose set forth.

ALBERT BROWN.
